Jarvis Hunt,
By Offield Balle & Scott, Atty.

UNITED STATES PATENT OFFICE.

JARVIS HUNT, OF CHICAGO, ILLINOIS.

GOLF BALL.

Application filed April 2, 1924. Serial No. 703,598.

To all whom it may concern:

Be it known that I, JARVIS HUNT, a citizen of the United States, and a resident of Chicago, in the county of Cook and State of Illinois, have invented certain new and useful Improvements in Golf Balls, of which the following is a specification.

This invention relates to golf balls, and has for its principal object to provide an improved arrangement of conformations on the surface thereof, whereby the frictional air resistance during flight produces rotation of the ball on a predetermined axis, and at the same time the proper balance and rolling properties of the ball are preserved to insure the desire accuracy on the putting green. The invention may best be understood from the drawings in which,

Figure 1 shows one form in which it may be embodied.

Figure 2 is a view taken from another angle, but with lines drawn on the surface to indicate the linear arrangement of projections with respect to the axis and equator of the sphere.

Figure 3 is an enlarged transverse section of one of the projections.

Figure 4 is a plan view of the projection shown in Figure 3.

As will be seen from the figures of the drawing, my invention consists in providing an improved form and arrangement of projections 10, 10 designed individually to have maximum efficiency in coacting with the air and being arranged on the surface of the ball so that the aggregate effect produces the desired axial rotation. One of these projections is illustrated in enlarged section in Figure 3, and in plan view in Figure 4

which show it is elongated in form, being rounded in its larger end, and tapering toward the other end. This shape is such as to offer minimum head resistance to the air when its blunt end is pointed in the direction

of flight, being substantially what is commonly known as "stream line". Accordingly, I arrange certain of these projections with their longitudinal axes extending on lines 10^a, 10^a curved from adjacent one pole

11, about the sides of the ball toward the opposite pole 12. Each of the series 10, 10 may terminate in any suitable manner near the poles, as for instance, at end zones 13, 13 of restricted area. These end zones may be used for the usual marks of identification such as trade marks or the like.

In order to preserve the desired balance of the ball, I also interpose shorter series 14, 14, of projections on lines 14^a, 14^a between adjacent series 10, 10, so as to produce approximate equal distribution of projections on the surface of the ball. Manifestly, any desired number of shorter series may be provided as required for this purpose.

The lines 10^a, and 14^a, upon which the projections are disposed are arranged at an oblique angle to any meridian, that is to say, a line formed by the intersection of an axial plane with the surface of the sphere, as illustrated in Figure 2.

A golf ball constructed in accordance with my invention is capable of being controlled in its flight to a much greater degree than ordinary balls, owing to the contour of the surface as described. The great frictional

resistance of the air during flight cooperates with the projections to give the ball a twisting or rotational movement about its normal axis. The peculiar shape of the projections affords maximum efficiency for this purpose.

Axial rotation of the ball in turn produces a tendency to bring the axis into line of flight, so as to present the least resistance to the air, and thus promote accuracy in flight without "pulling" or "slicing". This is accomplished in the present invention without affecting the balance of the ball by the interposition of shorter series of projections between longer series, as described. This arrangement also gives greater efficiency in producing axial rotation of the ball during flight, due to the increased number of series of projections at the equator, where they are most effective for the purpose described.

I claim as my invention:

1. A golf ball provided with a plurality of stream line projections with their longitudinal axes arranged in continuous lines extending between opposite poles and at angle inclined to the meridian lines thereof.

2. A golf ball provided with a plurality of series of linear conformations extending between opposite poles of the ball and inclined to the meridian lines thereof, said series being of varying lengths and more numerous at the equator than near the poles, whereby said conformations are distributed with substantial uniformity over the surface of the ball.

3. A golf ball provided with a plurality of series of linear conformations of substantially uniform size extending between op-

posite poles of the ball and inclined to the meridian lines thereof, said series being of varying lengths and more numerous at the equator than near the poles, whereby said conformations are distributed with substantial uniformity over the surface of the ball.

4. A golf ball provided with a plurality of series of elongated stream line projections with their longitudinal axes extending between opposite poles of the ball and inclined

to the meridian lines thereof, said series being of varying lengths and more numerous at the equator than near the poles, whereby said projections are distributed with substantial uniformity over the surface of the ball.

Signed at Chicago, Illinois, this 29th day of March 1924.

JARVIS HUNT.
